UNITED STATES PATENT OFFICE.

AUGUSTE GUILBERT-MARTIN, OF ST. DENIS, FRANCE.

GLASS TUBE FOR WATER-GAGES.

SPECIFICATION forming part of Letters Patent No. 332,920, dated December 22, 1885.

Application filed November 25, 1884. Serial No. 148,818. (No model.) Patented in France October 1, 1883, No. 157,799; in Belgium October 16, 1883, No. 62,898; in England October 17, 1883, No. 4,960; in Germany October 22, 1883, No. 26,920, and in Italy September 30, 1884, No. 374.

To all whom it may concern:

Be it known that I, AUGUSTE GUILBERT-MARTIN, of St. Denis, (Seine,) France, have invented certain new and useful Improvements 5 in Glass Gage-Tubes, of which the following is a full, clear, and exact description.

The object of my invention is to provide certain new and useful improvements in glass gage-tubes—such as steam-boiler gage, thermometer, and barometer tubes, &c.—whereby the upper end of the column of liquid can be more easily distinguished.

The invention consists in a glass tube in which a colored longitudinal strip is arranged 15 in front of a white or other bright strip.

Reference is to be had to the accompanying drawings, forming a part of this specification, in which similar letters of reference indicate corresponding parts in all the figures.

20 Figure 1 is a face view of my improved glass gage-tube. Fig. 2 is a longitudinal sectional elevation of the same. Fig. 3 is a sectional plan view of the same, on the line $x-x$, Fig. 1.

In the glass tube A a strip, B, of white or 25 other bright enamel, is incorporated, the width of the said strip preferably being about one-sixth of the circumference of the tube, and preferably the said strip is arranged on the outer surface of the tube, as shown. In front 30 of the said white or bright enamel strip B a colored enamel strip, D, is arranged on the middle of the same, the colored strip D being very much narrower than the white strip, so that it will show very distinctly on the same.

35 I prefer to make the strip D red. The bright or white strip B acts as a reflector, thus showing the colored strip more distinctly. The water C in the tube acts as a lens and magni-

fies that part of the colored strip below the level of the water, so that the part of strip D 40 below the level of the water appears broader than the part above it, and thus a break appears on the width of the colored strip at the level of the water, whereby the level of the water can be discovered more readily, especially when the water is not clear. 45

In case the liquid is not transparent—for instance, such as mercury, colored water, or alcohol—that part of the strip D below the level of the water is covered and concealed, 50 and only the part above the level of the water is visible, and thus the level of the water coincides with the bottom of the visible part of the colored strip D. I prefer to make the strips B D of enamel, but may make them of any 55 suitable material.

The tube must at all times be so arranged that the strips will be on that side opposite the one facing the observer.

Having thus described my invention, I claim 60 as new and desire to secure by Letters Patent—

1. As an improved article of manufacture, a glass gage or thermometer-tube having a colored strip arranged on and narrower than a bright strip, substantially as herein shown 65 and described.

2. A glass gage or thermometer-tube provided with a longitudinal colored strip or stripe on a white or bright strip, the colored strip being arranged nearer the inner surface of the 70 tube than the white or bright strip, substantially as herein shown and described.

AUGUSTE GUILBERT-MARTIN.
